REFRIGERATING APPARATUS

Leslie B. M. Buchanan, Springfield, Mass., assignor to Westinghouse Electric & Manufacturing Company, East Pittsburgh, Pa., a corporation of Pennsylvania

Application June 26, 1936, Serial No. 87,424

19 Claims.

(CL 62—4)

My invention relates to refrigerating apparatus of the type employing a plurality of evaporator elements operated at different mean temperatures and has for an object to provide improved apparatus of this character.

A further object of the invention is to provide an improved domestic type refrigerator and method of refrigeration wherein fluids may be more rapidly congealed than in prior apparatus of this kind.

A still further object of the invention is to effect quick freezing of water or other fluids in a conventional refrigerator cabinet without depressing the temperature of the food storage compartment to an undesirable degree and without excessively dehydrating the air therein.

A further object of my invention is to refrigerate one element of a refrigerating system to a relatively low temperature, prior to the refrigeration of a second element at a higher temperature during each cycle of the system.

These and other objects are effected by my invention, as will be apparent from the following description and claims taken in connection with the accompanying drawing, forming a part of this application, in which:

Fig. 1 is a sectional view of a portion of a domestic refrigerator having my improved refrigerating apparatus applied thereto;

Fig. 2 is a view of a detail of Fig. 1 shown in a different operating position;

Fig. 3 is a section of the detail shown in Fig. 2 and is taken along the line III—III of Fig. 1; and,

Fig. 4 is a modified view of some of the details shown in Fig. 1.

In prior refrigerating machines of the domestic type having a food storage compartment and a common evaporator therein for cooling the air in the compartment and for freezing fluids, quick freezing of the latter without excessively dehumidifying and cooling the air in the compartment has been difficult. If the temperature of the evaporator is maintained at a desirable value for cooling the food in the compartment, then congealing of fluids is slow and, if the temperature of the evaporator is lowered to effect quick congelation, then excessive cooling of the food and dehydration of the same is experienced.

To obviate this undesirable condition, it has been proposed to supply different compartments for food cooling and for congealing of fluids or freezing of water. Separate evaporator elements are provided for the respective compartments, which evaporators operate at different temperatures suitable for these purposes. This construc-

tion, while effective, is expensive. My invention may be applied to a cabinet construction such as this, but may also be applied to the less expensive type of construction wherein a single insulated food storage compartment is employed with a unitary refrigerating element for effecting the refrigeration of both the food products and the fluid to be congealed.

In practicing my invention, an evaporator structure may be disposed in a single compartment of the refrigerator which structure may take the outward appearance of a conventional evaporator. The walls of the evaporator structure and freezing trays define relatively high and low temperature evaporator elements. The walls are arranged in heat exchanging relation with the air in the compartment and the shelves are disposed within the walls and are shielded thereby from the air within the compartment.

In accordance with my invention, a conventional refrigerant condensing unit circulates refrigerant through the evaporating elements, preferably in series, so that refrigerant flows through the shelves and thence through the walls. Vaporized refrigerant is withdrawn from the walls. A reservoir for the storage of condensed refrigerant is connected to the shelves and walls, preferably between these elements. The purpose of the reservoir is to store more or less condensed refrigerant, so that it may or may not be delivered to the wall members for vaporization therein. A thermostatically operated device responsive to the temperature of the refrigerant delivered to the reservoir by the shelves or low temperature evaporator element, controls the storage of refrigerant in the reservoir.

The circulation of refrigerant is preferably controlled in response to the temperature of the walls or high temperature element. When the walls attain a predetermined high temperature, refrigerant is delivered to the shelves and thence to the reservoir. At this time, refrigerant is stored in the reservoir due to the relatively high temperature of the refrigerant therein, so that no refrigerant is delivered for vaporization in the wall members. When the shelves are depressed to a low temperature, the thermostatic control in the reservoir discharges the stored refrigerant to the walls for vaporization therein. As the temperature of the latter is depressed to the desired value, the condensing unit is stopped and refrigeration of both elements is terminated.

During the inactive periods of the condensing unit, the thermostatic device in the reservoir operates at a predetermined temperature to con-

dition the reservoir for storage of refrigerant therein. Thereafter, when the condensing unit is started at a predetermined higher temperature, the cycle is repeated. Accordingly, when 5 the condensing unit starts, the shelves are first refrigerated to a relatively low temperature and, thereafter, the walls are refrigerated to a relatively higher temperature.

Reference will now be had to Fig. 1 of the 10 drawing which discloses refrigerating apparatus constructed in accordance with one form of my invention applied to a conventional cabinet 10 having a compartment 11 for the storage of articles to be refrigerated. A refrigerant evaporating structure, generally indicated at 12, is disposed within the compartment 11 for cooling the air therein and for fluid congealing purposes such as, for example, the freezing of water. The structure 12 includes side walls 13 and 14 that 15 are provided with spaces 15 and 16, respectively, for refrigerant. A bottom wall 17 connects the bottoms of the side walls 13 and 14 and may or may not be refrigerated. A passage 18 is disclosed in the bottom wall 17 for conducting refrigerant from the wall 13 to the wall 14. The 20 upper portion of the wall 14 includes a header 19 from which refrigerant vaporized in the structure 12 is withdrawn.

The evaporating structure 12 may be suspended in the compartment 11, preferably by extensions 20 of the walls 13 and 14. The side and bottom walls define a chamber 21 therebetween which may be closed at the back by a rear wall 22. The rear wall 22 is connected to the side 25 walls 13 and 14 and preferably extends from the bottom wall 17 to the top of the extensions 20. The front of the chamber 21 may be closed by a door (not shown) in a well understood manner.

Arranged within the chamber 21 are shelves 23 30 and 24 having respective passages 25 and 26 formed therein for refrigerant. A conduit 27 is employed for conducting condensed refrigerant to the shelf passage 25 and a conduit 28 provides communication between the shelf passages 25 35 and 26. These connections provide for series flow of refrigerant through the shelves 23 and 24, but it will be understood that other methods of conducting refrigerant through the shelves may be employed. Trays 29 may be supported 40 by the shelves for the fluid to be congealed or frozen.

The walls 13 and 14 define an evaporating element that is maintained at a mean temperature suitable for refrigerating the air within the compartment 11 to a temperature value that is optimum for the storage of food. This value is sufficiently low for proper cooling of the air and high enough to prevent excessive dehydration thereof. The shelves 23 and 24 define an evaporating 55 element that is maintained at a lower mean temperature than the walls 13 and 14, so that faster freezing of fluid in the trays 29 is obtained than would be obtained at the higher mean wall temperature.

60 The air within the compartment 11 is shielded, substantially, by the various walls of the structure 12 from the relatively low temperature prevailing in the chamber 21 so that its temperature or vapor content is not affected to any material degree by the relatively cold air in the chamber 21.

65 Refrigerant is circulated through the shelves and walls of the evaporating structure 12 by any suitable refrigerating machine such as, for example, a hermetically sealed motor driven com-

pressor mechanism 31. The mechanism 31 withdraws vaporized refrigerant from the header 19 through a conduit 32 and compresses it to a relatively high value for delivery through a conduit 33 to a condenser shown diagrammatically 5 at 34. Cooling of the condenser 34 is effected in any suitable manner for liquefying the compressed vapor. Condensed refrigerant is delivered to the conduit 27 through a suitable pressure reducing device such as a conventional high 10 side float valve 35. The operation of a system of the compressor-condenser-expander cycle is well known and no description thereof is deemed necessary.

The motor compressor mechanism 31 is energized by electrical line conductors L₁ and L₂ controlled by a thermostatic switch 36 preferably responsive to the temperature of the wall 14. I disclose a thermostatic switch 36 of the expansible gas type, but it will be understood any suitable 20 thermostatically operated switch may be employed. As shown, the switch 36 includes a temperature-responsive element 37 secured to the wall 14 adjacent the header 19. As the operation of gas type thermostatic switches is well known, 25 no detailed description of the operation will be given other than to state that the switch is closed at a relatively high temperature of the wall 14 and is opened at a relatively low temperature thereof.

30 In accordance with my invention, means are provided for reducing the temperature of the shelves 23 and 24 to a relatively low degree each time the compressor mechanism 31 is operated to effect cooling of the walls 13 and 14 and, therefore, the air within the compartment 11. This 35 operation is effected by, first, evaporating refrigerant in the shelves and, subsequently, effecting evaporation in the walls.

The means for accomplishing this operation 40 includes a structure 40 that defines a reservoir 41 for storing variable quantities of condensed refrigerant (Figs. 1 to 3, inclusive). A conduit 42 is provided for conducting condensed and vaporous refrigerant from the shelf passage 26 to the reservoir 41 and a second conduit 43 provides communication between the reservoir 41 and the passage 15 of the wall 13. The latter conduit 43 defines an overflow device and may extend upwardly in the reservoir a predetermined distance 50 for determining the maximum depth and quantity of refrigerant to be stored therein, as shown in Fig. 1.

An inverted cup 44 is disposed coaxially with the conduit in telescopic relation and is supported by a thermostatic member or disc 45. The latter may be of bi-metal construction with the high expansive metal on top, so that, when it is relatively warm, it is in the position shown in Fig. 1, and, when cooled, it snaps to a position in 60 which it is curved in the opposite direction to that shown. Accordingly, the cup 44 is lowered into the refrigerant as shown in Fig. 2, whereby the depth and quantity of the refrigerant in the reservoir 41 is reduced as described hereinafter. 65 The disc 45 may be supported in any suitable manner as by lugs 46 formed within the reservoir structure 40.

The discharge end of the conduit 42 is disposed adjacent the thermostatic disc 45 whereby refrigerant entering the reservoir structure 40 flows in heat-exchanging relation over the disc 45 and then drops to the reservoir 41. The disc 45, therefore, is operated in response to the temperature of the refrigerant entering the reservoir 41. 70 75

When this temperature is at a relatively high value, the disc 45 is in its upper position and the maximum quantity of refrigerant, as determined by the elevation of the open end of the overflow conduit 43, is stored in the reservoir 41. When the temperature of the refrigerant entering the reservoir 41 is at a relatively low value, the disc 45 snaps downwardly to the position shown in Fig. 2 and the cup assumes a lowered position in Fig. 2 and the cup assumes a lowered position in 10 which it is telescoped with the conduit 43. As the cup 44 is of larger inside diameter than the outside diameter of the conduit 43, an annular passage is defined therebetween, which passage provides communication between the reservoir 41 and the conduit 43.

The conduit 43 is connected to the suction of the compressor unit 31 through the walls 13 and 14, so that a lower pressure prevails in the conduit 43 than in the reservoir 41. Condensed refrigerant will, therefore, rise in the annular passage between the cup 44 and the conduit 43 and overflow into the latter until the level of the condensed refrigerant in the reservoir 41 is depressed slightly below the bottom of the cup. 20 This level determines the minimum depth and quantity of refrigerant stored in the reservoir 41. At this time, the walls 13 and 14 are filled with refrigerant, the level of which is indicated by the dot and dash line in the header 19. (Fig. 1.) 25 When the maximum quantity of refrigerant is stored in the reservoir (Fig. 1) the walls 13 are devoid, substantially, of condensed refrigerant so that evaporation is effected only within the shelves 23 and 24. When the reservoir contains 30 its minimum quantity of refrigerant, the walls 13 and 14 contain condensed refrigerant in an amount represented by the difference in quantities of refrigerant stored by the reservoir and evaporation at this time is effected in the wall members 13 and 14.

Operation

The position of the apparatus, as shown in the drawing, is that which prevails during the inactive period of the condensing unit and just prior 45 to the starting thereof. At such times, the cup 44 and disc 45 are raised, as the temperature of the refrigerant in the reservoir 41 is above the value at which the disc snaps upwardly, said value being, for example, 25° F. When the temperature of 50 the wall 14 rises to a predetermined value of 29° F., for example, the thermostatic switch 36 closes for initiating operation of the motor compressor unit 31.

Condensed refrigerant from the condenser 55 passes to the shelves 23 and 24 through the float valve 35 and is vaporized in the shelves for abstracting heat from the material in the trays 29 in a well understood manner. Excess condensed refrigerant passed to the shelves, of course, passes 60 through conduit 42 and, after contacting the disc 45, collects in the reservoir 41. Vaporous refrigerant from the shelf passages 25 and 26 passes through the conduit 42, the reservoir structure 40, conduit 43, passages 13-18 and 16 of the walls 65 to the header 19 and thence to the compressor unit 31 through conduit 32. Refrigeration is now effected in the shelf passages 25 and 26 by evaporation and no cooling is effected by evaporation in the wall passages 15 and 16. Some cooling 70 of the walls 13 and 14 will be effected but it is relatively small, the amount of heat abstracted from the walls being only that added to the refrigerant vapor as superheat.

Some evaporation is effected in the reservoir 75 structure 40, but this may be reduced by covering

the structure with heat insulation (not shown). In any event, the cooling effect of the evaporation in the reservoir 41 is confined to the air in the chamber 21 containing the trays 29.

During this operation, the temperature of the shelves 23 and 25 is depressed with little reduction in temperature of the walls 13 and 14. As the temperature of the refrigerant contacting the bimetal disc 45 reaches a low value of 10 degrees, for example, the disc 45 and cup 44 snap downwardly, as shown in Fig. 2, the refrigerant level in the reservoir descends; the outflowing condensed refrigerant filling the wall passages 15 and 16 to a level shown in dotted lines in the header 19. Evaporation is immediately effected in the 15 wall passages 15 and 16 for cooling the air in the food compartment 11.

As refrigeration of the walls is initiated, the pressure and temperature of the refrigerant in the low side of the system rises due to the rapid 20 evaporation obtaining in the wall passages. Accordingly, as the walls are cooled, the temperature of the refrigerant in the shelves rises to a value of 18 degrees, for example. As operation of the compressor unit 31 continues, both the 25 shelves and wall are depressed in temperature to a value of say 16 degrees at which the thermostatic switch 36 operates to terminate operation of the unit 31. The inactive portion of the cycle 30 then follows.

As the temperature of the refrigerant in the reservoir 41 increases to 25 degrees, the disc 45 snaps upwardly to condition the reservoir for storage of refrigerant when operation of the compressor unit 31 is started, which operation is 35 effected when the temperature of the wall 14 rises to 29 degrees.

From the foregoing, it will be apparent that the shelves are operated at a lower mean temperature than the wall members; the former operating in the example recited between 29 degrees and 10 degrees and the wall members between 29 degrees and 16 degrees. By reducing the shelves to the relative low temperature of 10 degrees each time the system is cycled, fast 45 freezing or congelation of substances in the trays is effected. As the walls are operated at a higher minimum temperature or 16 degrees, and since the walls shield the shelves, it will be apparent less dehydration of the air in the compartment 50 55 60 65 70 75 80 ture evaporating element is within and shielded by the higher temperature element, it is to be understood that these elements may be separated or disposed in separated compartments 5 without departing from the spirit and scope of my invention.

While I have shown my invention in but two forms, it will be obvious to those skilled in the art that it is not so limited, but is susceptible 10 of various other changes and modifications without departing from the spirit thereof, and I desire, therefore, that only such limitations shall be placed thereupon as are imposed by the prior art or as are specifically set forth in the ap- 15 pended claims.

What I claim is:

1. In refrigerating apparatus, the combination of first and second evaporating elements, means for condensing refrigerant vaporized in said ele- 20 ments, means for conveying liquid refrigerant from the condensing means to said elements in such manner that liquid refrigerant normally flows into the first element in preference to the second element, and means responsive to a relatively low temperature of the refrigerant dis- 25 charged from the first evaporating element for admitting liquid refrigerant to said second element and being responsive to a relatively high temperature for passing only refrigerant vapor- 30 ized in the first element to said second element.

2. In a refrigerating system, the combination of refrigerant condensing means, an evaporator structure having first and second evaporating elements, means for conveying the condensed re- 35 frigerant to said evaporator structure, a reservoir for condensed refrigerant, and a thermostatically operated device arranged within the reservoir for varying the supply of refrigerant there- 40 in and movable, to a first position, wherein a relatively large amount of condensed refrigerant is stored in the reservoir and substantially no condensed refrigerant is delivered to the second evaporating element and movable, to a second position, wherein a relatively small amount of refrigerant is stored in the reservoir and con- 45 densed refrigerant is delivered to both of said evaporating elements.

3. In a refrigerating system, the combination of refrigerant condensing means, an evaporator structure having first and second evaporating elements, means for conveying the condensed refrigerant to said evaporator structure, a reservoir carried by said evaporator structure for storing condensed refrigerant therein, a device disposed 50 within the reservoir for controlling the storage of refrigerant therein, thermostatically-operated means responsive to the temperature of the refrigerant in the reservoir for actuating said device to a first position, wherein condensed refrigerant is stored in the reservoir and substantially no condensed refrigerant is delivered to said second evaporating element, and movable to a second position, wherein condensed refrigerant is dis- 55 charged from the reservoir and is delivered to both of said evaporating elements, and means responsive to the temperature of the second evaporating element for controlling the operation of the refrigerant condensing means.

4. In a refrigerating system, the combination of refrigerant condensing means, first and sec- 70 ond refrigerant evaporating elements, means for conveying condensed refrigerant from the condensing means to said evaporating elements so that it flows to the first evaporating element in preference to the second evaporating element, a

reservoir for condensed refrigerant, thermostatic means responsive to the temperature of the refrigerant in the reservoir for controlling the storage of condensed refrigerant therein, said thermostatic means being movable to a first position 5 wherein condensed refrigerant collects in the reservoir and substantially no condensed refrigerant is delivered to the second evaporating element, said thermostatic means being movable to a second position wherein condensed refrigerant is passed through the reservoir to the second element for vaporization therein, and means responsive to the temperature of the second element for controlling the operation of the refrigerant condensing means. 10

5. In a refrigerating system, the combination of refrigerant condensing means, first and second refrigerant evaporating elements, means for conveying condensed refrigerant serially through said first and second elements, a reservoir for 20 condensed refrigerant disposed between said first and second elements, and a thermostatic device responsive to the temperature of the refrigerant entering the reservoir for controlling the storage of refrigerant therein, said device being 25 movable to a first position in response to a relatively high temperature for effecting storage of condensed refrigerant in the reservoir with substantially no condensed refrigerant being delivered to the second evaporating element and movable to a second position in response to a relatively low temperature for passing condensed refrigerant through the reservoir to said second element for vaporization therein. 30

6. In a refrigerating system, the combination 35 of refrigerant condensing means, an evaporator structure including side wall members and shelves disposed therebetween, said sidewalls and shelves defining a pair of evaporating elements, a reservoir for condensed refrigerant, means for conveying condensed refrigerant serially through the shelves, the reservoir and the sidewalls in the order named, a thermostatically operated device arranged within the reservoir for controlling the storage of refrigerant therein, said device being 40 disposed in heat exchanging relation with the refrigerant entering the reservoir from the shelves and movable to a first position in response to a relatively high temperature of the refrigerant for effecting storage of refrigerant in the reservoir with substantially no condensed refrigerant being 45 delivered to the sidewalls, and being movable to a second position in response to a relatively low temperature of the refrigerant for passing condensed refrigerant to the sidewalls for vaporization 50 therein. 55

7. In a refrigerating system, the combination of refrigerant condensing means, an evaporator structure having first and second evaporating elements and a reservoir for the storage of condensed refrigerant, means for conveying condensed refrigerant from the condensing means through said first evaporating element, the reservoir, and the second evaporating element in the order named, a thermostatically-operated device arranged within the reservoir for controlling the storage of condensed refrigerant therein and disposed in heat exchanging relation with the refrigerant entering the reservoir from the first evaporating element, said device being movable to a first position in response to a relatively high temperature for effecting the storage of condensed refrigerant in the reservoir with substantially no condensed refrigerant being delivered to the second evaporating element and movable to a second position in response to a relatively low 70 temperature. 75

temperature for passing condensed refrigerant through the reservoir to said second evaporating element for vaporization therein.

8. In refrigerating apparatus, the combination of refrigerant condensing means, first and second refrigerant evaporating elements, a reservoir for condensed refrigerant, means for conveying condensed refrigerant in series through said first element, the reservoir and said second element in the order named, means for conveying vaporized refrigerant from the second evaporating element to the condensing means, a thermostatically operated device responsive to the temperature of the refrigerant within the reservoir for controlling the storage of refrigerant therein, said device being responsive to a predetermined relatively high temperature for effecting storage of condensed refrigerant in the reservoir with substantially no condensed refrigerant being delivered to the second evaporating element and being responsive to a predetermined relatively low temperature for effecting passage of condensed refrigerant through the reservoir to the second evaporating element for vaporization therein.
9. In refrigerating apparatus, the combination of a cabinet structure having a compartment therein, a plurality of wall members defining a refrigerant evaporating element and disposed in heat exchanging relation with the air in said compartment, a shelf disposed within said wall members and defining a second evaporating element disposed within said wall members for containing fluids, means defining a chamber for storing condensed refrigerant, means for withdrawing vaporized refrigerant from said wall members, means for condensing the withdrawn refrigerant and for translating it in series through said shelf, the chamber and said wall members in the order named, thermostatically operated means disposed within said chamber in heat exchanging relation with the refrigerant contained therein for controlling the storage of refrigerant in the chamber, said thermostatically operated means being responsive to a predetermined relatively high temperature for effecting storage of liquid refrigerant so that substantially no liquid refrigerant is delivered to the wall members and being responsive to a relatively low temperature for passing liquid refrigerant through the chamber to said wall members for evaporation therein, and means responsive to the temperature of the wall members for controlling the operation of the condensing means.
10. In refrigerating apparatus, the combination of a refrigerant circulating system in which variable quantities of refrigerant are to be circulated, a structure connected in said system and defining a reservoir for storing variable quantities of liquid refrigerant, means for admitting refrigerant to the reservoir, an outlet conduit extending upwardly in the reservoir and open at its top for defining the maximum depth of refrigerant to be stored, an inverted cup telescopically arranged with respect to the conduit, a thermostatic member responsive to the temperature of the refrigerant in the reservoir for supporting said cup and having upper and lower positions, said member, in its upper position, maintaining the cup elevated with respect to the conduit whereby the maximum quantity of refrigerant, as determined by the open top conduit, is stored in the reservoir and, in its lower position, maintaining the cup telescoped on the conduit so that the lower edge of the cup defines a lower level of refrigerant in the reservoir.

11. The method of cycling a refrigerating machine having relatively high and low temperature evaporating elements which comprises liquefying refrigerant for the evaporating elements in response to a predetermined high temperature of the high temperature element, effecting refrigeration of the low temperature element each time the high temperature element calls for refrigeration, substantially reducing refrigeration of the low temperature element and effecting refrigeration of the high temperature element when the low temperature element is satisfied in response to a predetermined low temperature of the low temperature element, and stopping liquefaction of refrigerant when the high temperature element is satisfied in response to a predetermined low temperature of the high temperature element.

12. The method of cycling a refrigerating machine having relatively high and low temperature evaporating elements which comprises liquefying refrigerant for the evaporating elements in response to a predetermined high temperature of the high temperature element, effecting refrigeration of the low temperature element each time the high temperature element calls for refrigeration, substantially reducing refrigeration of the low temperature element and effecting refrigeration of the high temperature element when the low temperature element is satisfied in response to a predetermined low temperature of the low temperature element, and stopping liquefaction of refrigerant when the high temperature element is satisfied in response to a predetermined low temperature of the high temperature element, which latter low temperature is of a higher value than the low temperature in response to which refrigeration of the low temperature element is stopped.

13. The method of cycling a refrigerating machine having first and second evaporating elements which comprises periodically circulating liquid refrigerant to the elements, delivering a portion of the circulated refrigerant to one of said elements for vaporization and withholding a second portion of the refrigerant from circulation each time the machine is started, and subsequently releasing said withheld refrigerant to the second evaporating element for vaporization therein when the temperature of the first evaporating element has been depressed to a predetermined value.

14. The method of cycling a refrigerating machine having relatively high and low temperature evaporating elements which comprises liquefying refrigerant for the evaporating elements in response to a predetermined high temperature of the high temperature element, delivering a portion of the liquefied refrigerant for vaporization in the low temperature element and withholding from circulation a second portion of the liquefied refrigerant each time the machine is cycled, subsequently releasing said portion of withheld refrigerant to the high temperature element when the temperature of the low temperature element has been depressed to a predetermined low value and terminating the liquefaction and delivery of refrigerant to both of said elements in response to a predetermined low temperature of the high temperature element, which latter low temperature is of a higher value than said temperature at which the withheld refrigerant is released.

15. In refrigerating apparatus, the combination of a cabinet structure, an evaporator disposed within the cabinet structure and embodying wall members and a shelf enclosed thereby,

- 5 said wall members and shelf defining separate refrigerant evaporating elements, a refrigerant condensing unit, means for periodically operating the condensing unit, and means for automatically effecting, during each operation of the condensing unit, vaporization of refrigerant in said shelf at relatively low temperature and, thereafter, in the wall members at a relatively higher temperature.
- 10 16. In refrigerating apparatus, the combination of a cabinet having a cooling compartment therein, an evaporator structure disposed within said compartment and including a pair of spaced wall members and a shelf disposed there-
15 between, said wall members defining a relatively high temperature evaporating element for cooling the air in said compartment and said shelf defining a relatively low temperature evaporating element for congealing fluids, a refrigerant con-
20 densing unit, means for periodically effecting operation of the condensing unit, and means automatically actuated each time the condensing unit is operated, for effecting vaporization of refrigerant first in the shelf and, subsequently, in the
25 wall members.
17. In refrigerating apparatus, the combination of a cabinet structure, an evaporator disposed within the cabinet structure, said evaporator structure embodying wall members defining
30 a relatively high temperature evaporating element and a shelf enclosed by the wall members and defining a relatively low temperature evaporating element, a mechanism for condensing refrigerant evaporated in the high and low tem-
35 perature evaporating elements, means responsive to the temperature of the high temperature evaporating element for effecting periodic operation of the refrigerant condensing mechanism, and means for automatically effecting, during each
40 operation of the condensing mechanism, vapor-

ization of refrigerant in the low temperature element first and, thereafter, vaporization of refrigerant in the high temperature element.

18. In a refrigerating system the combination of first and second evaporating elements, means for supplying liquid refrigerant preferentially to the first element and secondarily to the second element, and means responsive to a relatively low temperature of the refrigerant discharged from the first evaporating element for admitting liquid refrigerant to said second evaporating element and responsive to a relatively high temperature for passing refrigerant vaporized in the first element to said second element.

19. In a refrigerating system, the combination of first and second evaporating elements, means for condensing refrigerant vaporized in said element, means for supplying the condensed refrigerant to the evaporating elements so that it flows into the first evaporating element until a predetermined amount is contained therein and thence into the second evaporating element, means for storing a predetermined quantity of condensed refrigerant in a portion of the system other than the second element, and a thermo-
20 static device exposed to the refrigerant dis-
25 charged from the first element for controlling the storage of refrigerant in said storing means, said device being responsive to a relatively high
30 temperature of the refrigerant for effecting stor-
35 age of refrigerant whereby condensed refrigerant is delivered to the first evaporator element for vaporization and being responsive to a relatively low temperature of the refrigerant for rendering the storing means ineffective to store said quantity of refrigerant whereby condensed refrigerant is delivered to the second evaporating element for vaporization.

LESLIE B. M. BUCHANAN. 40

CERTIFICATE OF CORRECTION.

Patent No. 2,133,954.

October 25, 1938.

LESLIE B. M. BUCHANAN.

It is hereby certified that error appears in the printed specification of the above numbered patent requiring correction as follows: Page 3, second column, line 11, after the syllable "wardly" and before the comma insert the word and; and that the said Letters Patent should be read with this correction therein that the same may conform to the record of the case in the Patent Office.

Signed and sealed this 6th day of December, A. D. 1938.

Henry Van Arsdale

(Seal)

Acting Commissioner of Patents.
